UNITED STATES PATENT OFFICE.

MORGAN J. LEWIS, OF MASSILLON, OHIO.

GARAGE-DOOR OPENER.

Application filed April 3, 1923. Serial No. 629,601.

This invention relates to door openers and more particularly to a power actuated device adapted for opening or closing heavy doors such as are used upon garages and similar buildings.

The objects of the invention are to provide a motor operated device arranged to open and close the doors, means being provided for automatically stopping the motor when the doors reach the fully open or fully closed position, a reversing switch being automatically operated by the motor to automatically reverse the motor with each operation of the mechanism; to provide means for holding the doors locked in the closed position; and to generally improve and simplify devices of this character.

The above and other objects may be attained by constructing the device in the manner illustrated in the accompanying drawings, in which—

Figure 1 is a plan view of a pair of swinging doors provided with a door opening device embodying the invention;

Fig. 2, a section on the line 2—2, Fig. 1; Fig. 3, a section on the line 3—3, Fig. 1; Fig. 4, a section on the line 4—4, Fig. 1; Fig. 5, a plan view of the switch;

Fig. 6, a fragmentary perspective view of a portion of the switch operating mechanism; and Fig. 7, a detail perspective view of another portion of the switch operating mechanism.

Similar numerals refer to similar parts throughout the drawings.

A pair of hinged or swinging doors 1—1, are shown to normally close an entrance. A motor 2, is mounted above the doors, preferably near one side of the door opening, upon a bracket 3, the shaft 4, thereof having a pinion 5 fixed thereon and meshing with a gear 6 fixed upon a shaft 7 which is journaled through the gear housing 8.

A gear 9 is fixed upon the long shaft 10 and meshes with the gear 7, said shaft 10 being journaled through the gear housing 8 at one end and through the bracket 11 at the other end.

A bevel gear 12 is fixed upon each end of the shaft 10 and meshes with a bevel gear 13 fixed upon the thread shaft 14, which is journaled at opposite ends in the bearings 15 and 16 depending from the brackets 3 and 11.

A nut 17 is mounted upon each of the

threaded shafts 14 and the bifurcated portion 18 of a link 19 is pivoted thereto as at 20, the opposite end of each link being pivoted to the ears 21 upon the adjacent door 1, as by a pin 22 which may be provided with a pull chain 23 for removing the pivot pin when desired.

The switch for reversing the motor is mounted upon an insulation block 24 carried upon a bracket 25 which may be supported from the gear housing 8. One line wire 26 is connected to the three-way switch 27 placed in a convenient location to be manually operated and the other line wire 28 is connected to the terminal 29 upon the block 24.

A terminal 30 is mounted upon the block 24 and extends above and in vertical alignment with the terminal 29 and is connected by the wire 31 with the three-way switch, the wire 32 connecting the three way switch with a terminal 34 similar to the terminal 30.

A terminal 35, similar to the terminal 29, is located beneath the terminal 34 and is connected by a bus-bar or the like, as indicated at 36 with the terminal 37, similar to the terminals 30 and 34, and located between the same. The terminal 35 is connected as at 38 with a terminal 39 upon the opposite side of the block and similar to the terminals 30 and 34. A terminal 40 similar to the terminal 29, is located beneath the terminal 39 and connected as by the bus-bar 41 with the terminal 34.

A pair of terminals 42 and 43 are located upon the same side of the block with the terminal 39 and are of a construction similar to the terminal 39, excepting that each is provided near its lower end with a contact lip 44 for engagement with the switch blade as will be later described. The terminals 39, 40, 42 and 43 are connected by the wires 45 with the motor in the usual manner to provide for reversing the motor when the switch is reversed.

An inverted, U-shaped bracket 46 is mounted upon the switch block between the two sets of terminals above described, and is provided with the depending arms 47 in which are journaled the end portions of the switch arm 48 which is provided with a crank portion 49 connected by a coil spring 50 with the lower end of the half round portion 51 of the switch lever 52 which is pivoted upon the ear 53 formed upon the

top of the bracket 46, a longitudinal slot 54 being provided in the bracket to permit movement of the lever.

Three switch blades 55 are fixed at their central portions upon the switch arm 48 and provided with the bifurcated extremities 56 for engagement with the various terminals.

A threaded shaft 57 is concentrically mounted upon the shaft 7 and fixed thereto in any suitable manner, said screw threaded shaft extending outward toward the lever 52 and having a nut 58 mounted thereon and provided with a reduced, threaded neck 59 upon which are mounted a pair of adjusting nuts 60, between which is clamped the depending arm 61 of the slotted bar 62, which is provided with the longitudinal slot 63 through which the switch lever 52 extends.

Assuming the parts to be in the position shown in Fig. 1, with the doors closed, in order to start the motor to open the doors, the three-way switch 27 is manually operated, completing the circuit to the motor and starting the motor to operate in a direction to rotate the shaft 10 and through it the screw threaded shafts 14 in a direction to move the nut 17 forward or outward upon the screw threaded shaft and through the links 19 to force the doors open.

The screw threaded shaft 57 will, during this operation, be rotated in a direction to move the nut 58 toward the outer end of the same, carrying with it the slotted bar 62. This bar will swing the switch lever 52 upon its pivot until the same passes over the center, when the spring 50 will snap the switch arm 48 into the opposite position, stopping the motor as the doors reach the fully opened position.

With the parts in this position, the doors may be closed by again operating the three-way switch, the reversing switch being in the reverse position, causing the motor to operate in the reverse direction, moving the nuts 17 backward upon the threaded shafts 14 to close the doors.

At the same time, the nut 58 will be moved backward upon the threaded shaft 57 and the bar 62 thereon will operate to throw the switch lever 52 back to the first position, as shown in Fig. 4, stopping the motor as the doors reach the closed position.

It will be seen that with the doors in the closed position, it will be impossible for

them to be opened from the outside by an unauthorized person, as the links 19 connect the doors to the nuts 17 which cannot be moved longitudinally upon the threaded shafts 14, excepting by the rotation of the shafts, which, of course, cannot be accomplished from the outside.

I claim:—

1. A door operating mechanism including in combination with a swinging door, a motor, a threaded shaft located at right angles to the normal plane of the door, a nut upon the shaft, a link pivotally connecting the nut and the door, means operatively connecting the motor with the threaded shaft, a quick throw reversing and stopping switch, a threaded shaft operated by the motor, a nut upon the shaft, a slotted bar fixed to the nut and an operating lever upon the switch engaging the slotted bar for automatically operating the switch as the door reaches the fully opened or fully closed position.

2. A door operating mechanism including in combination with a swinging door, a motor, a threaded shaft journaled adjacent to the motor, gearing operatively connecting the shaft to the motor, a nut mounted upon the shaft and held against rotation, a link pivotally connected at opposite ends to the nut and to the swinging door, a second threaded shaft arranged to be rotated by the motor, a nut upon said second threaded shaft provided with a slotted arm, and a quick throw reversing and stopping switch having an operating lever engaging the slot in said arm and arranged to control the motor.

3. A door opening mechanism including, in combination with a movable door, a motor, a threaded shaft, a nut upon the threaded shaft, a link connecting the nut and the door, means operatively connecting the motor with the threaded shaft, a quick throw reversing and stopping switch, a threaded shaft operated by the motor, a nut upon the last named shaft, a slotted bar fixed to the nut, and an operating lever upon the switch engaging the slotted bar for automatically operating the switch as the door reaches the fully opened or fully closed position.

In testimony that I claim the above, I have hereunto subscribed my name,

MORGAN J. LEWIS.
